UNITED STATES PATENT OFFICE.

PERCY L. WARNE, OF CAMBRIA, WYOMING.

DESIGN FOR A ROPE-TIGHTENER.

SPECIFICATION forming part of Design No. 30,374, dated March 21, 1899.

Application filed September 6, 1898. Serial No. 690,339. Term of patent 14 years.

To all whom it may concern:

Be it known that I, PERCY L. WARNE, a citizen of the United States, residing at Cambria, in the county of Weston and State of Wyoming, have invented and produced a new and original Design for Rope-Tighteners, of which the following is a specification, reference being had to the accompanying drawings, forming a part thereof.

10 Figure 1 is a plan view of my rope-tightener, and Fig. 2 is a section on line 2 2 of Fig. 1.

As shown in the drawings, the leading feature of my invention in design for rope-tightener consists in the substantially elliptical form of the major portion, the circular outline of the minor portion springing from one end of the major portion, the lateral expansion of the major portion, and the transverse 15 web extending upwardly from the major portion.

Referring now particularly to the drawings,

my design consists in the substantially elliptical form of the major portion *a*, having a similar opening therein. An extension at one 25 end of the major portion is formed circular in outline and with a circular opening centrally thereof. At the sides of the major portion the outline is extended laterally to form parallelograms *e* and *f*, and extending from 30 one of these parallelograms to the other is an upwardly-extending flange *g*.

Having thus described my invention, what I claim as new, and desire to secure by Letters Patent, is—

The design for a rope-tightener, substantially as shown and described.

In testimony whereof I affix my signature in the presence of two witnesses.

PERCY L. WARNE.
